ABSTRACT OF THE DISCLOSURE

Superconductive apparatus includes a superconductive coil, coil-carrying means extending at least partly around and carrying the coil so that the coil is situated at least in part within the coil-carrying means, and support means enclosing and supporting the coil-carrying means with the coil therein. The coil-carrying means has an elongated wall of U-shaped cross section in which the coil is situated and is formed with spaces in the form of elongated passages through which a refrigerating medium is adapted to flow.

Our invention relates to superconductive apparatus.

In apparatus of this type, which includes a superconductive coil, it is necessary for this latter coil to be situated in a thermally insulated manner within a housing in which the coil is refrigerated. In this type of structure difficulties are encountered in absorbing the forces which arise between the coil and the housing in which it is situated, upon excitation or rotary movement of the coil. In order to solve this latter problem it has already been proposed to provide a construction where a thermally insulated and refrigerated superconductive coil is situated within a housing arranged within a hollow space of a multipartite elongated coil-carrier which is surrounded by thermal insulation and which is fixedly positioned within and with respect to the housing by means of mechanical force-transmitting elements.

In a structure of this latter type it is possible to use a pressure-sensitive thermal insulation of great heat resistance composed, for example, of reflecting, wrinkled foils, since the forces between the coil-carrier and the housing are absorbed by the mechanical force-transmitting elements referred to above. These mechanical force-transmitting elements can take the form of tension rods or, in the case of relatively small forces, of spacers which are stressed in compression.

With this latter type of structure the refrigerating of the superconductive coil is brought about by way of a refrigerating coil placed within the thermal insulation about the coil-carrier for the superconductive coil.

It is a primary object of our invention to improve a construction of this latter type.

In particular, it has been found that with this latter type of construction the situation of the refrigerating structure outside of the coil-carrying structure, for the superconductive coil, does not provide the most efficient refrigeration of the superconductive coil, and it is therefore an object of our invention to provide a structure of the above type capable of refrigerating the superconductive coil in a manner superior to structures heretofore provided for this purpose.

A more specific object of our invention is to provide refrigerating of the superconductive coil directly within the coil-carrier itself, rather than by way of a refrigerating structure which is located at the exterior of the carrier for the superconductive coil.

Thus, in accordance with our invention, the supercon-

2

ductive apparatus includes a superconductive coil and a coil-carrying means which extends at least in part around and carries the superconductive coil with the latter situated within the coil-carrying means of our invention. In accordance with our invention this coil-carrying means is itself formed with spaces through which the refrigerating medium is adapted to flow, and this coil-carrying means is enclosed by a support means within which are located the coil-carrying means together with the superconductive coil situated therein.

According to one embodiment of our invention the coil-carrying means can be formed with elongated passages which form the spaces through which the refrigerating means is adapted to flow, while according to another embodiment of our invention the coil-carrying means includes a netting situated in the immediate vicinity of the superconductive coil and having meshes which form the spaces through which the refrigerating medium is adapted to flow.

Our invention is illustrated by way of example in the accompanying drawings which form part of this application and in which:

FIG. 1 is a partly sectional, schematic, perspective illustration of a superconductive apparatus which incorporates the structure of our invention, the section of FIG. 1 being taken in a plane which extends transversely through the superconductive coils and the structure carrying the same, so that the part of the apparatus which is located only on one side of this latter plane is visible in FIG. 1;

FIG. 2a is a fragmentary sectional elevation, on an enlarged scale as compared to FIG. 1, showing the details of that part of the structure of FIG. 1 which is enclosed within the dot-dash circle A;

FIG. 2b is a transverse section through a superconductive coil and the structure directly associated therewith, the plane of FIG. 2b being displaced from the plane of FIG. 2a;

FIG. 3 is a transverse section through another embodiment of a coil-supporting structure according to our invention; and

FIG. 4 is a schematic top plan view of the superconductive apparatus indicating the plan according to which the refrigerating medium is distributed through the apparatus.

The two-pole winding which is schematically illustrated in section in FIG. 1 consists of a pair of elliptical coils 1 and 2 through which the coil current i flows in the same directions. As a result forces of repulsion form between the coil parts 3-6, and these forces are absorbed by the tension rods 7-10. These tension rods are connected with the support means which encloses and supports the coils, and the details of this latter support means are illustrated in FIGS. 2a, 2b, and 3. The coils together with the supporting structure therefor are situated within elongated tubular housings 14, and within these housings 14 the coils are enclosed within the pair of support means 13 in which the coils are embedded. The tension rods 7-10, as well as the additional tension rods 11, serve to maintain the coils together with their supporting structure in a predetermined position within the housings 14. The additional tension rods 11 are connected with the walls of the housing 14 by way of units 11' which do not form part of the present invention and which serve to limit the extent of yieldability of the tension rods 11.

FIG. 2a shows the details of that part of the structure of FIG. 1 which is located within the dot-dash circle A, and it is to be understood that this construction is duplicated at corresponding parts of the superconductive apparatus. Thus, referring to FIG. 2a it will be seen that the winding wires 12 of the coil 1 are enclosed within an elong-

gated support means 13 to which the thermally insulated tension rods 10 and 11 are connected. These tension rods fixedly hold the support means 13 in the desired location within the tubular housing 14. This latter housing is made up of a pair of parts 15 and 16 which are joined together in a vacuum-tight manner by means of the sealing rings 17. In the evacuated interior space 18 of the housing 14, between the walls of the latter and the support means 13, is situated a pressure-sensitive thermal insulation. The tension rods 10 and 11 are situated within vacuum-tight metal sleeves 19 and 20 in which they are surrounded by the thermal insulation 21. The metal sleeve 19 is composed of a pair of telescoped parts which are soldered together at the location 22 indicated in FIG. 2a. This soldering takes place during assembly of the apparatus, after the support means 13 has been situated within the housing 14 at the desired location by threading of the tension rods into threaded openings which are formed in the support means 13, as indicated in FIG. 2a. In order to compensate for thermally induced changes in length, the metal sleeve 20 is at least partly of an elastic construction. In the illustrated example the sleeve 20 is provided for this purpose with a vacuum-tight metal bellows 23. While the tension rods 10 serve only to interconnect the pair of coil support means indicated in FIG. 1, where both of these support means are situated practically at the superconducting temperature, the tension rods 11 extend from the support means for the superconductive coils to housing parts which are at room temperature. Therefore, in order to provide a refrigerating shield for these tension rods 11, the conduits 24 through which the refrigeration medium flows are coiled about the tension rods 11.

The coil-support means 13 has a multipartite construction. In the illustrated example it is composed of two parts which form for the support means 13 a cross section providing the support means with a hollow interior space within which the completely wound coil can be introduced. At locations of the parts of the support means 13 which are displaced from the locations to which the tension rods are connected, screws 25 serve to fasten the parts of the support means 13 to each other, as indicated in FIG. 2b. By way of sealing elements 26 it is possible to prevent any vapors situated within the support means 13 from reaching the evacuated intermediate chamber 18 between the support means 13 and the housing 14.

In the particular example illustrated in FIGS. 2a and 2b, the wires 12 of the coil are situated within a coil carrying means 27 which is of a U-shaped cross section and which extends along and partly surrounds the coil so that the latter is situated within the coil-carrying means 27. Thus, the support means 13 encloses the coil-carrying means 27 with the windings 12 situated therein. This coil-carrying means 27 of our invention is formed with spaces through which the cooling or refrigerating medium is adapted to flow, and in the example of FIGS. 2a and 2b, these spaces for the refrigerating medium take the form of elongated passages 28 formed in the coil-carrying means 27. FIG. 2b illustrates the manner in which the passages for the refrigerating medium communicate with the tubular conduit assembly 24 through which the refrigerating medium is supplied to and withdrawn from the passages 28.

In the embodiment of the device which is illustrated in FIG. 3, the spaces through which the refrigerating medium is adapted to flow take the form of meshes of a wire netting. In this embodiment the coil-carrying means 29 is also of a U-shaped cross section. This coil-carrying means 29 has a pair of opposed side walls along whose inner surfaces the layers of metal netting 30 and 31 are situated. The refrigerating medium flows through the meshes of the metal netting 30 and 31. For this purpose the conduits 32 for the refrigerating medium are connected with the opposed ends of the coil-carrying means 13. Only one of the tubular conduits 32 for the refrigerating medium is illustrated in FIG. 3.

FIG. 3 also illustrates the construction of the coil. An

insulating foil 33 is situated at the inner periphery of the coil body. Surrounding and engaging the insulating foil 33 are several layers of non-insulated coil wire windings 12 made of superconductive material. In order to avoid an electrical connection between the coil wire and the metal netting 30 and 31, insulating filaments 34 are wound into the ends of each layer of coil windings 12. An electrical connection between the several layers is prevented by means of thermally conductive refrigerating foils 35 which extend from the outer sides of the superconductive coil into the interior thereof between the several layers of windings, and these foils 35 are themselves covered with an insulating coating 36. The refrigerating foils 35 may be made, for example of eloxated (anodized) aluminum. These refrigerating foils 35 serve not only to insulate the successive winding layers from each other but also to provide a good thermal connection between the interior of the superconductive coil and the refrigerating medium which flows through the metal netting. The successive foils 35 are alternately in engagement with the metal netting components 30 and 31.

The coil-carrying means 29 is closed by means of a layer of insulating foil 37 and a metal foil 38 which is soldered to the outer free edges of the coil-carrying means 29 in a fluid-tight manner preventing the flow of helium, used for the refrigerating medium, through the enclosure formed by the part of the coil-carrying means 29 which is formed by a wall of U-shaped cross section and the foil 38 which closes off the interior space of this wall of U-shaped cross section.

It is preferred to fix the superconductive coil within its supporting structure by means of a pourable mass which is rigid at the superconducting temperatures. For this purpose a pourable mass composed of oil or grease 35 is suitable. This mass fills the space 39 between the coil-carrying means 29 and the inner surface of the support means 13. In order to prevent escape of vapors of the pourable mass through the support means 13 into the vacuum chamber 18, the sealing elements 40 and 41 are provided. The sealing elements 40 are situated at the interface between the components of the support means 13, while the sealing elements 41 surround the conduits 32 at the region of the exterior surface of the support means 13. In the embodiment of FIG. 3 the support means 13 is positioned within the housing 14 not by way of tension rods but instead by means of supporting pins 42 which are stressed in compression.

FIG. 4 illustrates schematically the manner in which the refrigerating liquid is distributed through the superconductive apparatus. A pair of supply conduits 43 and four discharge conduits 44 are provided. The refrigerant distribution systems schematically illustrated in FIG. 4 takes place within the support means 13 which encloses the coil together with the coil-carrying means within 55 which the coil itself is situated. In the embodiments of FIGS. 2a and 2b, the refrigerant circulation indicated in FIG. 4 is achieved by making only part of the elongated tubes 28 of rectangular cross section hollow, so that in this way the flow of the refrigerant is blocked at predetermined locations to provide the circulation illustrated in FIG. 4. Thus, those parts of the flow-controlling structure for the refrigerant which are not hollow are made of massive copper bars. A coil-carrying means 27 of this type can be very simply constructed in such a way that the tubular passages 28 of rectangular cross section and the solid massive copper bars 28 of rectangular cross section are soldered one to the other, so that the refrigerant will flow only through the hollow portions of the structure and will be blocked by the solid copper bars.

In the embodiment of FIG. 3, the circulation of the refrigerant which is provided according to the plan shown in FIG. 4 is achieved by filling selected portions of the spaces in which the metal netting is situated either with a metal or a plastic filling material so that the flow of refrigerant is blocked at the locations where the latter

filling material is situated, thus providing the circulation indicated in FIG. 4.

We claim:

1. In a superconductive apparatus, a superconductive coil, coil-carrying means extending at least partly around and carrying said coil, so that said coil is situated at least in part within said coil-carrying means, said coil-carrying means having an elongated wall of U-shaped cross section in which said coil is situated, said elongated wall containing spaces in the form of elongated passages through which a refrigerating medium is adapted to flow, said passages being completely enclosed in said elongated wall, and support means enclosing and supporting said coil-carrying means with said coil therein.

2. In a superconductive apparatus, a superconductive coil, coil-carrying means extending at least partly around and carrying said coil, so that said coil is situated at least in part within said coil-carrying means, said coil-carrying means being formed with spaces through which a refrigerating medium is adapted to flow and including a netting at least partly surrounding said coil and having meshes which form said spaces, and support means enclosing and supporting said coil-carrying means with said coil therein.

3. In a superconductive apparatus, a superconductive coil, coil-carrying means extending at least partly around and carrying said coil, so that said coil is situated at least in part within said coil-carrying means, said coil-carrying means having an elongated wall of U-shaped cross section in which said coil is situated and being formed with spaces through which a refrigerating medium is adapted to flow and including a netting situated in said wall of U-shaped cross-section between said wall and coil, said netting having meshes which form said spaces through which the refrigerating medium is adapted to flow, and support means enclosing and supporting said coil-carrying means with said coil therein.

4. The combination of claim 3 and wherein a plurality of refrigerating foils which are adapted to have a thermally conductive connection with the refrigerating me-

dium from at least one side of said coil into the interior thereof.

5. The combination of claim 4 and wherein said refrigerating foils are covered with an electrically non-conductive, thermally conductive coating.

10 6. In a superconductive apparatus, a superconductive coil, coil-carrying means extending at least partly around and carrying said coil, so that said coil is situated at least in part within said coil-carrying means, said coil-carrying means being formed with spaces through which a refrigerating medium is adapted to flow, support means enclosing and supporting said coil-carrying means with said coil therein, and a pourable mass which is rigid at superconducting temperatures surrounding said coil-carrying means and said coil therein and situated within said support means fixedly positioning said coil-carrying means and coil therein.

15 7. The combination of claim 6 and wherein said pourable mass is grease.

8. The combination of claim 3 and wherein at least one of said means has a fluid-tight construction preventing the flow of the refrigerating medium therethrough.
